PUMPING APPARATUS

Waldemar F. Mayer, Los Angeles, Calif., assignor
to Byron Jackson Co., Huntington Park, Calif.,
a corporation of Delaware

Application July 18, 1938, Serial No. 219,802

7 Claims. (Cl. 103—52)

This invention relates generally to hydraulic piston pumps, and particularly to a duplex hydraulic piston pump intended to provide steady, pulseless discharge.

A broad object of the invention is to reduce the cost and improve the performance, particularly with respect to smoothness of operation and of fluid discharge, of duplex hydraulic piston pumps.

10 The invention is particularly useful in mud pumps for handling drilling mud in connection with deep well drilling by the rotary method. Pumps employed in this service are subjected to extremely severe operating conditions because 15 of the large volumes and high pressures required, and also because of the abrasive nature of the drilling mud. Direct-acting duplex steam pumps are widely used, but are not ideally suited to this service for several reasons. The replacement cost 20 of worn parts is very high, in many instances amounting to as much as the initial cost of the pump while drilling a single well; the discharge is pulsating, causing destructive vibration of the drill pipe and connecting lines; and the steam consumption is unduly high because of the necessity of utilizing the full stroke of the pistons, with 25 no cut-off.

Another object of the invention is to provide 30 a duplex pump which is capable of withstanding the severe operating conditions set forth above, and which will deliver drilling mud in a steady, pulseless stream at a wide range of pressures and volumes. The efficiency is greatly increased by the provision of a hydraulic pump capable of being 35 operated by motive liquid supplied by a highly efficient centrifugal pump, which in turn may be driven by any efficient and economical prime mover such as a steam turbine, an electric motor, or an internal combustion engine.

40 A still further object is to provide a duplex pump having a set of long stroke pistons and a set of short stroke pistons, the latter operating during reversal of the stroke of the former to provide continuous, steady discharge.

45 Other objects and advantages will be apparent as the description proceeds, reference being had to the accompanying drawings, wherein:

Fig. 1 is a plan view of a pump constructed in accordance with this invention;

50 Fig. 2 is a side elevation thereof;

Fig. 3 is an end elevation;

Fig. 4 is an enlarged plan view of the central portion of the pump, with parts broken away as indicated on line 4—4 of Fig. 5, to illustrate the 55 general arrangement of the valve mechanisms;

Fig. 5 is a transverse vertical section taken on line 5—5 of Figs. 4 and 6;

Fig. 6 is a central longitudinal vertical section taken on line 6—6 of Figs. 4 and 7;

Fig. 7 is a central transverse vertical section taken on line 7—7 of Figs. 4 and 6; and

Fig. 8 is a longitudinal vertical section taken on line 8—8 of Figs. 4 and 7.

Referring to the drawings, the pump comprises generally a central body A in which are housed the motive liquid valves and the pump liquid suction and discharge valves, and to opposite sides of which are secured a pair of elongated cylinders B, B' in axial alignment with each other. A pair of relatively short cylinders C, C' are also 15 formed in the central body A, in axial alignment with each other and disposed at right angles to the cylinders B, B'.

The main cylinders B, B' are of double-walled construction, comprising inner cylinders 11, 11' 20 and concentric outer shells 12, 12' defining therebetween annular channels 13, 13' communicating at their outer ends with the interiors of the inner cylinders 11, 11'. At their inner ends the channels 13, 13' communicate respectively with chambers 2 14, 14' in the central body A. Each of these chambers has valved connection through suction and discharge valves with a common pump liquid suction header 17 and a common pump liquid discharge chamber 18, respectively. Thus, as shown 30 in Fig. 5, suction valve 15' and discharge valve 16' communicate chamber 14' with the suction header 17 and with the discharge chamber 18, respectively.

A pair of pistons 21, 21' are secured to opposite ends of a piston rod 22 for reciprocation in unison in the cylinders 11, 11', respectively, the piston rod extending through a partition 23 separating the inner ends of the cylinders. On admission of motive liquid under pressure alternately to the cylinders on the inner sides of the pistons, the latter are reciprocated to force pump liquid out of one cylinder ahead of the respective piston and to draw pump liquid into the other cylinder behind the piston. Spent motive liquid is 45 forced out of the other cylinder ahead of its piston. The valve mechanism for controlling the admission and discharge of motive liquid will be described hereinafter.

Referring now to the short cylinders C, C', 50 shown most clearly in Fig. 7, each is provided with an inner liner 26, 26' spaced from the outer wall to form channels 27, 27' corresponding to channels 13, 13' of the long cylinders. The channels 27, 27' communicate respectively with chambers 55

28 (Fig. 5) and 28' (Fig. 8), the former having valved connection with the suction header 17 through suction valve 29 and with the discharge chamber 18 through discharge valve 30, similar 5 valves (not shown) being provided for the chamber 28'.

Pistons 34, 34' are reciprocable in unison in the cylinders C, C', being secured to opposite ends of a piston rod 35. As in the case of the long 10 cylinders, motive liquid is admitted alternately to the cylinders C, C' to reciprocate the pistons 34, 34' and draw pump liquid from the suction header 17 and force it under pressure into the discharge chamber 18. Valve mechanism is provided for controlling the admission of motive liquid 15 to the cylinders.

The valve mechanisms for controlling the flow of motive liquid to and from the two pairs of cylinders will now be described. As stated hereinabove, the short stroke pistons 34, 34' are reciprocated only during the reversal period of the long stroke pistons, to provide continuous, steady 20 discharge of pump liquid. To this end, each pair of cylinders is provided with a reversing valve 25 which is actuated by the pistons of the other pair of cylinders as they approach the end of their stroke. As shown in Fig. 4, a pair of reversing valves, generally designated R and R', are housed within the upper portion of the central body A, 30 being disposed at right angles to each other, the valve R' being disposed parallel to the long, or main, cylinders B, B' and the valve R being parallel to the short, or auxiliary, cylinders C, C'.

Valve R comprises a pair of connected shuttle 35 valves 41, 41' (Fig. 7) shiftable from a right-hand position, as shown, wherein motive liquid is admitted from an inlet 42 to a port 43 leading to main cylinder 11' and spent motive liquid is exhausted from main cylinder 11' through port 44 40 to discharge chamber 45, to a left-hand position wherein motive liquid is admitted to cylinder 11' through port 44 and spent motive liquid is exhausted from cylinder 11' through port 43 to the discharge chamber 45.

45 Valve R' (Fig. 6) is identical with valve R, having a pair of shuttle valves 51, 51' controlling the admission of motive liquid from inlet 42 alternately through ports 52, 52' to the auxiliary cylinders C, C'. To opposite ends of valve R' are 50 secured valve rods 53, 53' having connection through levers 54, 54' with rocker shafts 55, 55', whereby on oscillation of the shafts the valve will be reciprocated. As shown in Fig. 5, the rocker shafts are journaled in the central body 55 on upright axes and extend downwardly therein to adjacent the cylinders 11, 11'. On the lower ends of the shafts are actuating fingers 56, 56' which project into the cylinders in the paths of sleeves 57, 57' secured to the piston rod 22 adjacent the pistons 21, 21'. As each piston approaches the inner end of its stroke a finger 56 or 56' is engaged by the respective sleeve 57 or 57' to rock the shafts 55, 55' and reverse the valve R'.

60 Valve R is similarly provided with valve rods 61, 61', levers 62, 62', rock shafts 63, 63', and actuating fingers 64, 64' engageable by sleeves 65, 65' on the piston rod 35 of the auxiliary pistons 34, 34', whereby valve R is reversed as the latter 65 pistons approach the end of their stroke.

66 Referring once more to Figs. 1, 2, and 3, the pump liquid inlet and discharge connections are indicated at 71 and 72, respectively, and the motive liquid inlet 42 and discharge 73.

75 From the foregoing description it is believed

that the mode of operation of the pump will be understood. Motive liquid is supplied to the inlet 42 in a steady stream at uniform pressure from a suitable source such as a centrifugal pump. The drawings depict the positions of parts when 5 the main pistons are travelling to the right, as viewed in Fig. 6. Valve R (Fig. 7), which controls the main piston, is shifted to the right to admit motive liquid to cylinder B' on the inner side of piston 21', and to exhaust spent motive liquid 10 from cylinder B. The auxiliary pistons 34, 34' are at rest at the right-hand ends of their cylinders, with motive liquid being applied to cylinder C' due to the position of valve R' to the left.

The actuating sleeve 57 associated with piston 15 21 is about to engage the actuating finger 56, and when this occurs valve R' will be shifted to the right to admit motive liquid to the left-hand auxiliary cylinder C. The auxiliary pistons will thus be moved to the left, and after travelling only a 20 short distance the sleeve 65' will engage actuating finger 64', reversing the main valve R. The auxiliary pistons continue to travel to the left until piston 34 engages the cover plate at the outer end of the cylinder C, the piston speed of 25 both sets of pistons being greatly reduced, however, during simultaneous movement. This is due to the fact that the volume of motive liquid remains constant, and is divided between the two cylinders. After the auxiliary pistons have come 30 to rest the speed of the main pistons increases, inasmuch as they then receive the total displacement of the motive liquid pump. On approaching the left end of their stroke, the actuating sleeve 57' associated with main piston 21' engages actuating finger 56' to reverse the auxiliary valve R', and the operation is repeated.

While it is believed preferable to provide auxiliary pistons with a stroke only sufficiently long to take care of reversal of the main pistons, it 40 will be appreciated that the relative lengths of the strokes may be any desired ratio.

By the provision of pistons actuated directly by motive liquid, many advantages are realized. The pressure differential across the pistons is 45 very small, resulting in practically entire elimination of wear on the cylinder walls and pistons. The piston rods are always under tension, thus removing the limitation imposed on the stroke length when the rods are under compression. 50 With at least one long stroke unit the frequency of reversals is reduced, effecting material savings in wear and tear on the valves, particularly the pump liquid suction and discharge valves. Other advantages will be apparent to those skilled in 55 this art.

I claim:

1. Hydraulic pumping apparatus comprising, in combination: a pair of reciprocating piston pump units of the fluid pressure actuated type, 60 common motive liquid inlet and outlet connections and pump liquid inlet and discharge connections to said units, valve means for controlling the flow of motive liquid to and from each of said units to actuate the same, the valve means 65 associated with each unit being actuated in predetermined relation to the piston movement of the other unit whereby each unit pumps during the stroke-reversing period of the other unit to maintain continuous flow of motive and pump 70 liquids, the stroke of one of said units being relatively short in comparison to the stroke of said other unit and of minimum length sufficient only to maintain continuous flow of liquid during instantaneous reversal of the piston of the other 75

unit whereby the idle time of said other unit is minimized.

2. Apparatus as defined in claim 1, in which the valve means associated with the short-stroke unit is actuated adjacent the end of the stroke of the long-stroke unit, and the valve means associated with the long-stroke unit is actuated adjacent the beginning of the stroke of the short-stroke unit.
- 10 3. Hydraulic pumping apparatus comprising a pair of aligned cylinders, a pair of interconnected pistons reciprocable in unison in said cylinders, a second pair of aligned cylinders disposed substantially at right angles to said first named cylinders, interconnected pistons reciprocable in said second-named cylinders, motive liquid inlet and outlet connections and pump liquid inlet and discharge connections to said pump, a pair of motive liquid valve means in said central body, each of said valve means being disposed parallel to one of said pairs of cylinders 10 and having operative connection therewith for actuating the valves in predetermined timed relationship to the movement of the pistons parallel thereto, and motive liquid connections from each valve means to the cylinders at right angles 15 thereto.
- 15 5. Apparatus as defined in claim 3, in which one of said pairs of cylinders are relatively short in comparison to the length of said other pair.
- 20 6. Apparatus as defined in claim 4, in which said second-named pair of cylinders are relatively short and are disposed within said central body.
- 25 7. Apparatus as defined in claim 4, in which said motive liquid inlet and outlet connections 25 and said pump liquid inlet and discharge connections are formed in said central body.

WALDEMAR F. MAYER.
